UNITED STATES PATENT OFFICE.

CHARLES L. ENGEL AND WALTER S. ENGEL, OF KANSAS CITY, MISSOURI.

BOOK CONSTRUCTION.

Application filed February 4, 1924. Serial No. 690,448.

To all whom it may concern:

Be it known that we, CHARLES L. ENGEL and WALTER S. ENGEL, citizens of the United States, residing at Kansas City, in the 5 county of Jackson and State of Missouri, have invented a certain new and useful Improvement in Book Constructions, of which the following is a specification.

Our invention relates to improvements in 10 book constructions.

It relates particularly to the construction of books adapted for use as books of record, which are heavy and are subjected to rough usage.

15 One of the objects of our invention is to provide a novel means for hinging the covers to the back of the book, which is simple, cheap to make, strong and durable, not liable to get out of order, and which presents a 20 neat appearance.

A further object of our invention, is the provision of novel means for attaching the covers to the back, which eliminates such accessory means for fastening the part together as rivets, stitching, etc.

25 A further object of our invention, is the provision of novel means for binding the edges of the covers.

Still another object of our invention, is to 30 provide a novel binding strip, which may be quickly and easily fitted on the edge of a cover, and which has novel means by which it may be securely fastened thereto, without such accessory fastening devices as rivets.

35 The novel features of our invention are, hereinafter fully described and claimed.

In the accompanying drawing which illustrates the preferred embodiment of our invention,

40 Fig. 1, is a plan view, partly broken away, of a book back and covers provided with our improvement.

Fig. 2, is an enlarged section on the line 2—2 of Fig. 1.

45 Fig. 3, is a perspective view of the outer back member.

Fig. 4, is an enlarged section on the line 4—4 of Fig. 1.

50 Fig. 5, is an enlarged section on the line 5—5 of Fig. 1.

Fig. 6, is a perspective view of one of the corner binding caps.

Similar reference characters designate 55 similar parts in the different views.

The back of the book comprises an inner channel sheet metal back member 1, and an

outer channel back member 2, which is fitted to the outer side of the member 1, to which it may be secured in any suitable manner, as by screws 3, having heads at their inner 60 end and fitted in threaded holes in the member 2. The latter may be of any suitable material, such as aluminum or vulcanized fibre.

Opposite longitudinal edges of the member 1, are provided with barrels 4, in which are mounted respectively two pintles 5.

6 designates two metal hinge plates at opposite sides respectively of the back, each plate 6 having at its inner edge barrels 7, 70 through which extends the adjacent pinte 5.

The back member 2, has at each end an inwardly extending arcuate flange 8, which is arranged to cover the adjacent ends of the pintles 5, to prevent their removal, accidentally or otherwise.

9 designates two outer cover members, each of which may be composed of heavy cardboard or other material, and upon the inner side of which is fastened the adjacent hinge member 6.

Respectively mounted upon the inner sides of the outer cover members 9 are two inner cover members 10, which may be heavy cardboard and which respectively overlap the hinge plates 6. Each of the latter is provided with a longitudinal row of perforations 11, which constitute openings, through which the adjacent cover member 10, is pressed, such pressed portion being glued to 90 the inner side of the adjacent outer cover member 9, (see the left cover in Fig. 2), thereby securely attaching the cover members 9 and 10 to the hinge plates 6, without the use of rivets, stitching, or other accessory fastening means.

Each cover has each end edge and its outer longitudinal edge bound with a channel binding strip of metal, preferably, such binding strip or member being designated by 12, Figs. 4 and 5. Each member 12 has an inwardly extending oblique portion 13 which fits against the bevelled outer edge of the cover member 9. The latter has on its inner side adjacent to and parallel with each end edge and outer longitudinal edge a raised portion 14, Figs. 4 and 5 upon which each adjacent strip or member 12 rests. Each of the latter has at its inner upper edge a longitudinal portion 15 forming a shoulder which engages the inner edge 110 of the adjacent raised portion 14. Such

longitudinal portion has inwardly extending from it a longitudinal flange 16. The adjacent inner cover member 10 overlaps the flanges 16, thereby securely holding the 5 binding members or strips 12 in position on the outer cover member 9. In assembling the parts, the binding members 12 are sprung over the raised portions 14 of the members 9, after which the inner cover 10 members 10 are fastened to the members 9, as described.

17 designates sheet metal corner caps which may be mounted on each outer corner of each cover, said caps overlapping the 15 adjacent binding members 12 to which the caps may be secured as by soldering.

The raised portions 14 of each cover member 9 form in said member a depression in which the adjacent member 10 is mounted, 20 the inner side of the latter being flush with the inner sides of the binding members 12.

We do not limit our invention to the structure shown and described, as many 25 modifications, within the scope of the appended claims, may be made without departing from the spirit of our invention.

What we claim is:—

1. In book construction, an outer cover member, having on its inner side a raised 30 portion adjacent to and parallel with one edge thereof an edge binding member embracing the outer side and said edge and extending inwardly over the said raised portion and embracing the inner edge of the 35 latter and having a flange extending inwardly from said raised portion, and an inner cover member fastened to the inner side of said outer cover member and overlapping said flange.

2. In book construction, a back, an inner cover member, an outer cover member fastened to the outer side of said inner member and having adjacent to one of its edges and parallel therewith a raised portion, an edge 40

binding member embracing the outer side 45 of said outer cover member and the inner side and inner edge of said raised portion and having extending inwardly from said raised portion a flange, the inner cover member being fastened to the inner side of the 50 outer cover member and overlapping said flange, and a hinge member disposed between said cover members and hinged to the back and having a transverse opening, said cover members being glued to each other 55 through said opening.

3. In book construction, an edge binding member having a channel adapted to receive an edge portion of a cover member and having at its inner edge portion a depressed 60 portion forming a shoulder adapted to engage the inner edge of a raised portion on the inner side of the cover member and having an inwardly extending flange at the inner side of said shoulder adapted when 65 the cover member is in said channel to lie against the inner side thereof.

4. In book construction, a cover member having on its inner side a raised portion adjacent to and parallel with its end edges 70 and outer longitudinal edge, channel edge binding members embracing the outer side of said cover member and the inner side and inner edge of said raised portion, each having extending inwardly from said raised 75 portion a flange, an inner cover member fastened to the inner side of the first named cover member and overlapping said flanges, and two corner caps embracing and secured to one of said binding members and respectively embracing and secured to the adjacent ends of the other two edge binding members.

In testimony whereof we have signed our names to this specification.

CHARLES L. ENGEL.
WALTER S. ENGEL.
